CARL H. BISSELL AND JOHN J. DOSSERT, OF SYRACUSE, NEW YORK, ASSIGNEES TO CROUSE-HINDS COMPANY, OF SYRACUSE, NEW YORK, A CORPORATION OF NEW YORK.

MEANS FOR CONNECTING ELECTRICAL APPLIANCES TO CONDUIT OUTLET-BOXES.

1,185,168.

Specification of Letters Patent.

Patented May 30, 1916.

Application filed December 27, 1910. Serial No. 599,457.

To all whom it may concern:

Be it known that we, CARL H. BISSELL and JOHN J. DOSSERT, of Syracuse, in the county of Onondaga and State of New York, have invented a certain new and useful Means for Connecting Electrical Appliances to Conduit Outlet-Boxes, of which the following is a specification.

This invention relates to means for connecting electrical appliances to conduit outlet boxes and has for its object a particularly simple and efficient device adapted to support electrical appliances of different sizes and makes; and to this end the invention consists in the combinations and constructions hereinafter set forth and claimed.

In describing this invention reference is had to the accompanying drawing in which like characters designate corresponding parts in all the views.

Figure 1 is a plan of one form of our invention. Fig. 2 is an elevation thereof. Fig. 3 is a sectional view taken on line "A—A" Fig. 1. Fig. 4 is an elevation taken 25 at a right angle to Fig. 2. Fig. 5 is a view similar to Fig. 4 showing the position of the flexible end wall of one of the slots before the bridge which normally extends into said slot has been placed in position. Fig. 6 30 is a plan of the blank form from which one of the members seen in the foregoing figures is formed. Fig. 7 is a fragmentary view of a conduit outlet box provided with our invention, a snap switch being shown as carried by the support. Fig. 8 is an elevation looking to the left in Fig. 7. Fig. 9 is a plan of a modified form of our invention. Fig. 10 is a section on line "B—B", Fig. 9.

1 is the conduit outlet box which may be 40 of any desirable form, size and construction, said box having any suitable means, as the nipple 2, for the inlet and outlet of the electric wires. The box 1 is formed with an opening 3 in one side thereof, such opening 45 being here shown as circular in form, and the margin 4 of the wall around the opening being formed with a notch 5.

6 is a member constituting part of the means for supporting an electrical appliance 50 as the switch 7, said member being a sheet metal plate annular in form. 8 is a bridge also constituting part of the means for supporting an electrical appliance and coacting with the plate 6 and extending diametrically across the central opening thereof, the

bridge having tongues 9, 10 at its ends for engaging the inner surface of the margin of the wall around the opening 3.

In the illustrated embodiment of our invention the end portions 11 of the bridge 8 30 extend through slots or guides formed in diametrically opposite lugs 12, 13 projecting from the inner edge of the annular plate 6 and bent inwardly through the opening 3 at an angle to such plate 6, as seen in Figs. 65 2 and 3, and preferably one of such lugs, as the lug 13, is divided in order that a portion thereof, as the portion 14 forming the outer end wall of the slot may be bent outwardly, as seen in Fig. 5, permitting the 70 end of the bridge 8 to be passed therein. The portions 11 of the bridge extending through the slots are of less width than the intermediate portion of the bridge and thus shoulders 15 are formed which hold the 75 bridge from endwise movement in the slots. In placing the bridge in position one of these portions 11 is inserted endwisely through the closed slot of the lug 12 and the other portion 11 is moved laterally in 80 the slot in the lug 13 through the open end of the slot and when in position the flexible side 14 is pressed in position to close the slot. However, as seen in Figs. 9 and 10 both slots may be closed at their ends and 85 the bridge formed bow shape, as shown at 16, such bridge being flattened into a plane when the end portions 17 thereof have been inserted through the eyes 18.

One of the tongues of the bridge, as the 90 tongue 10, is reduced in width and is designed to move through the notch 5 in the margin of the wall around the passage 3, and beyond the plane of the inner side of 95 said margin and to move out of alignment with the notch and into engagement with said inner side of the margin when the plate is turned about its axis. After the plate and bridge have been assembled the tongue 9 is inserted under the portion of the margin 4 diametrically opposite the notch 5, and the tongue 10 moved through the notch 5 and then out of alignment with the notch to interlock with said margin.

The electrical appliance 7 is a snap 105 switch, supported by the plate 6 and bridge 8 and comprises a pair of attaching screws 19 which thread in one pair of a plurality of pairs of holes 20 in the bridge and clamp the plate and bridge on the margin 4. 110

These pairs of holes 20 are located at different distances from the axis of the plate and the holes of each pair are located diametrically opposite each other.

- 5 The plate 6 is also formed with means for engaging the edge of the margin 4 and centering the plate 6, such means being here shown as lugs 21 projecting from the inner margin of the annular plate 6 and bent inwardly and backwardly into a position parallel to the plate 6 so that their under edge will engage the edge of said margin.

In use the plates 6 are formed of different areas or with central openings of different sizes, in order to form bases for different sizes of commercial switches and the holes 20 are spaced apart so that one of such pairs of holes is in position to receive the attaching screws of a switch of a certain make, so that the supporting means is adapted to receive the attaching screws of switches of standard sizes and makes. The plate 6 is adjustable about its axis in order to so position the switch that the sight opening thereof may be arranged so as to be conveniently read, the sight openings in the various makes of switches occupying different positions relative to the attaching screws as will be understood by those skilled in the art.

What we claim is:

1. In combination, a conduit outlet box having a circular opening in one wall thereof and a notch leading from said opening, an electrical appliance for connection to wires in the box, and means for attaching the appliances to the box comprising a member engaging the outer surfaces of the wall of the box adjacent said opening and provided with a passage in alignment with said opening, a second member for engaging the inner face of the wall of the box adjacent the opening therein and having a length greater than the diameter of said opening, the second member being movable into and out of the box through said openings in the wall thereof when its longer axis is in registration with a diameter of said opening intersecting the notch, and non-removable from the box when its longer axis is out of registration with the last-named diameter, one of said members being movable toward and from the other and means for moving one of said members relatively to the other and clamping said members against the coacting faces of the wall of the box, substantially as and for the purpose described.
2. In an electrical appliance and in combination, a conduit outlet box having a circular opening through one wall thereof and a notch in said wall leading from the opening, a sheet metal ring resting against the outer face of said wall and overhanging the edge of the opening, a one piece sheet metal

strip carried by said ring and of greater length than the diameter of the opening and non-removable through the same when its longer axis is out of registration with a diameter of the opening intersecting the notch, an electrical device seating on said ring, and means for retaining the device in place and for clamping the ring and strip against outer and inner faces, respectively, of the wall of the box, substantially as and for the purpose specified.

3. In an electrical appliance and in combination, a supporting and connecting device comprising a member in the form of a flat ring provided with laterally extending lugs having openings therethrough, and a second member in the form of a flat strip extending through the openings in the lugs and provided with a plurality of sets of openings, said opening being exposed through the opening in the first-named member, substantially as and for the purpose set forth.

4. The combination with a conduit outlet box having a circular opening, the margin of the wall around said opening being formed with a notch, and means for supporting an electrical appliance connected to wires in the box, said means comprising an annular plate engaging the outer surface of the margin of the wall around the opening, means for engaging the inner surface of the margin, the last-mentioned means comprising an offset tongue movable through the notch beyond the inner face of said margin and a tongue projecting from the inner edge of the annular plate and backwardly toward the outer margin of said plate, the end of the last-mentioned tongue engaging the edge of said margin of the wall around the opening, and the plate being movable about its axis moving the first-mentioned tongue out of alignment with the notch, and means for clamping the means engaging the inner surface of said margin toward the plate substantially as and for the purpose described.

5. The combination with a conduit outlet box having an opening; of means for supporting an electrical appliance connected to wires in the box, said means comprising a plate engaging the outer face of the margin of the wall around said opening, and having a central opening and lugs extending at an angle to the plate and being formed with slots, and a bridge extending across the opening and having its end portions extending through the slots, substantially as and for the purpose set forth.

6. The combination with a conduit outlet box having an opening; of means for supporting an electrical appliance connected to wires in the box, said means comprising a plate engaging the outer face of the margin of the wall around said opening, and having

- a central opening, and lugs extending at a right angle to the plate and being formed with slots, and a bridge extending across the opening and having its ends extending through the slots, and one of the lugs having a flexible portion forming one of the walls of the slot in such lug, substantially as and for the purpose described.
7. The combination with a conduit outlet box having an opening; of means for supporting an electrical appliance connected to wires in the box, said means comprising a plate engaging the outer face of the margin of the wall around said opening, and having a central opening, and lugs extending at a right angle to the plate and being formed with slots, and a bridge extending across the opening and having its ends extending through the slots, and shoulders for engaging opposing faces of the lugs, and one of the lugs having a flexible wall at one end of the slot therein, substantially as and for the purpose specified.
8. The combination with a conduit outlet box having an opening in one wall thereof; of supporting means comprising parts for engaging inner and outer surfaces of the margin of the wall around said opening, one part being movable toward and from the other, and an electrical appliance mounted on the outer part and having an attaching screw threading into the inner part of the supporting means and serving to clamp the parts of the supporting means to the margin of said wall, substantially as and for the purpose specified.
9. The combination with a conduit outlet box having an opening in one wall thereof, the margin of the wall around said opening being formed with a notch; of supporting means comprising parts for engaging the inner and outer surfaces of said margin, the part engaging the inner margin being formed with a tongue movable through the notch and out of alignment with the notch into engagement with the inner face of the margin of said wall, and an electrical appliance supported by said means and including an attaching screw threading into the part engaging the inner surface of said margin

and serving to clamp the parts of the supporting means on the margin of said wall, substantially as and for the purpose set forth.

10. The combination with a conduit outlet box having a circular opening in one wall thereof; of supporting means comprising an annular plate engaging the outer face of the margin of said wall and a bridge detachable from the plate and extending diametrically thereof and having tongues at its opposite ends for engaging the inner surface of the margin of said wall, and an electrical appliance mounted on the plate and having an attaching screw threading into the bridge and serving to clamp the plate and bridge on the margin of said wall, substantially as and for the purpose described.

11. The combination with a conduit outlet box having a circular opening, the margin of the wall around said opening being formed with a notch; of supporting means comprising an annular plate engaging the outer surface of the margin of the wall around the opening, the plate being formed with diametrically disposed lugs extending at an angle thereto through the opening and formed with slots, and a bridge having its ends extending through the slots, the bridge having tongues at its ends for engaging the inner surface of the margin of said wall, one of the tongues being movable through the notch beyond the inner face of the margin of the wall around said opening, and the plate being movable about its axis for moving said tongue out of alignment with the notch, and an electrical appliance mounted on the plate and having an attaching screw threading into the bridge, substantially as and for the purpose set forth.

In testimony whereof, we have hereunto signed our names in the presence of two attesting witnesses, at Syracuse, in the county of Onondaga, in the State of New York, this 6th day of December 1910.

CARL H. BISSELL.
JOHN J. DOSSERT.
